EDWARD CUNNIF and JOSEPH H. COOKSON, of NEW BEDFORD, MASSACHUSETTS,
ASSIGNORS TO DRAPER COMPANY, OF HOPEDEALE, MASSACHUSETTS, A CORPORA-
TION OF MAINE.

LOOM-SHUTTLE.

No. 906,390.

Specification of Letters Patent.

Patented Dec. 8, 1908.

Application filed April 23, 1908. Serial No. 428,724.

To all whom it may concern:

Be it known that we, EDWARD CUNNIF and JOSEPH H. COOKSON, citizens of the United States, and residents of New Bedford, county of Bristol, State of Massachusetts, have invented an Improvement in Loom-Shuttles, of which the following description, in connection with the accompanying drawing, is a specification, like letters 10 on the drawing representing like parts.

This invention relates to shuttles of the type used in looms wherein a bobbin is inserted automatically in the working shuttle while the loom is in motion, and it has for 15 its particular object the production of improved and novel means for guiding the bobbin into proper position when inserted in the shuttle.

The various novel features of our invention will be fully described in the subjoined specification and particularly pointed out in the following claims.

Figure 1 is a top plan view of the bobbin-holding end of a loom-shuttle with one embodiment of our invention applied thereto; Fig. 2 is a partial longitudinal section on the line 2—2, Fig. 1; Fig. 3 is a horizontal sectional view on the line 3—3, Fig. 2.

The shuttle-body 1 has a bobbin-receiving 30 opening 2, as usual in shuttles of this character, and at one end of the opening the shuttle wood is vertically recessed from the top downward, as at 3, for a purpose to be described.

In our invention we form the holding 35 jaws of a relatively thin strip of spring-metal, folded or bent upon itself between its ends and then out-turned to form the jaws, instead of having the jaws milled out of a heavy bar, as heretofore, as we can make 40 the jaws much more easily and at less cost, and in addition we gain very considerably in elasticity of the jaws.

The spring metal strip, of suitable width 45 and thickness, is bent or folded upon itself as at 4, Fig. 3, between its ends and substantially in parallelism, constituting the jaw bases, and then the strip is bent outward at 5, and again bent nearly into parallelism, 50 forming the opposite jaws 6, which are grooved vertically on their inner faces at 7 to engage the usual rings on the bobbin head.

As shown best in Fig. 3 the folded portion

constituting the jaw bases is inserted in the recess 3 and a spreader 8, which is preferably a block of metal of suitable thickness, is pushed in between the parallel portions of the jaw bases, separating and holding them firmly seated in the recess in close contact 60 with its side walls.

The jaw bases and the spreader are apertured to receive the retaining bolt 9 extended transversely through the shuttle body, the bolt-hole being counterbored as usual to receive at one end the head of the bolt and at the other end the nut 10 into which the bolt is screwed.

As shown clearly in Fig. 3 the shuttle-wood is cut away adjacent the jaws at 11 70 to permit the separation thereof when the bobbin is inserted, this being usual practice.

The inclined guide 12 located between the jaws is transversely concaved in our invention, to insure a more complete control and 75 positive guidance of the bobbin-head of an incoming bobbin and cause the same to be in proper alinement with the longitudinal axis of the shuttle.

The guide is made of resilient metal, and 80 at its lower end it is bent back at 13, Fig. 2, to extend between the bottom of the recess 3 and the lower edges of the jaw bases and the spreader 8, the side walls of the recess being grooved in usual manner to receive the 85 extension.

At its upper end the guide is bent down 90 at 14 and then rearwardly extended at 15 upon the tops of the spreader and the jaw bases, and the sides of the recess are undercut or grooved at 3^x, see dotted lines Fig. 1, to receive the edges of the extension 15.

The extremity of the extension is bent to 95 form a downturned transverse lip 16 which enters a notch 17, Fig. 2, in the top of the spreader 8, similar notches being formed in the tops of the jaw bases, the engagement of the lip with the notches holding the guide 12 from displacement in the direction of the length of the shuttle.

By making the spreader of the proper thickness the jaw bases are separated just the requisite distance to fit tightly within the walls of the recess 3, the bend 4 abutting against the rear end of the latter, so that a firm seat is attained for the jaws, the bolt 9 preventing displacement during the operation of the shuttle in the loom.

By making the jaws from a strip of spring metal it will be obvious that the cost is reduced to a minimum and the formation of the notches 7 is simplified, the bending or 5 folding of the strip bringing the bases of the jaws into parallelism in readiness to be inserted in the shuttle.

Should the shuttle wood shrink sufficiently to enlarge the recess 3 sufficiently to loosen 10 the jaws this can be easily remedied by substituting a slightly thicker spreader, thereby saving the jaws and obviating fitting the shuttle with a new pair.

Having fully described our invention, 15 what we claim as new and desire to secure by Letters Patent is:—

1. A loom-shuttle having a bobbin-receiving opening, resilient holding-jaws mounted in the shuttle-body at one end of the opening, to engage and hold the head of a bob- 20

bin, and a transversely-concave, inclined guide between the jaws.

2. A loom-shuttle having a bobbin-receiving opening, opposed jaws mounted in the shuttle-body at one end of said opening, to 25 engage and hold the head of a bobbin, an inclined, transversely-concave guide for the bobbin head, located between the jaws, and extensions at the upper and lower ends of the guide extended rearwardly and fixedly 30 held in the shuttle-body.

In testimony whereof, we have signed our names to this specification, in the presence of two subscribing witnesses.

EDWARD CUNNIFF.
JOSEPH H. COOKSON.
